UNITED STATES PATENT OFFICE.

LESTER E. GESELL, OF THIEF RIVER FALLS, MINNESOTA.

PROPELLED MECHANISM FOR DREDGES, &c.

1,125,088.

Specification of Letters Patent.

Patented Jan. 19, 1915.

Application filed May 24, 1913. Serial No. 769,744.

To all whom it may concern:

Be it known that I, LESTER E. GESELL, a citizen of the United States, residing at Thief River Falls, in the county of Red Lake, and State of Minnesota, have invented certain new and useful Improvements in Propelling Mechanism for Dredges, &c., of which the following is a specification.

10 This invention relates to improved propelling mechanism for dredges, excavating machines, and various other machines of like character, and the primary object thereof is to provide novel and peculiar means whereby the entire frame or dredge support may be propelled forward by the operation of suitable mechanism carried thereby, the frame being supported through the medium of a plurality of runners or shoes arranged to straddle an excavation, and by means of which motion is imparted to the dredge, the runners being advanced according to the operation of any suitable power source carried upon the frame.

25 A further object of the invention contemplates the provision of a specially constructed dredge frame or support wherein means is provided for operating specially arranged chains and pulleys to actuate the runners upon which the frame is supported, certain of the runners acting as supports for the entire frame while the frame itself moves forwardly thereupon until certain of the other runners engage the ground and support the frame while the first mentioned runners are again positioned to allow the frame to again advance or move forwardly thereupon.

30 A still further object of the invention resides in the provision of an upright supporting frame upon which the main frame of the dredge or machine is at times supported, the said main frame being adjusted vertically upon the upright frame to permit the runners carried by the said main frame to be drawn or lifted out of engagement with the ground for forwarding the dredge until the runners of the upright frame engage the forward runners of the main frame, this operation being repeated to forward the entire machine as occasion demands.

35 The invention still further resides in the provision of means including specially devised clutch mechanism disposed upon the

bed of the main frame for reversing the operation or direction of rotation of certain of the gear wheels carried by the said frame, the operation of the said gears adapted to in turn control the movement of the chains for vertically adjusting the main frame and advancing the upright frame for forwarding or propelling the dredge in a manner to be hereinafter fully described.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is a side elevation of a dredge frame or support constructed in accordance with my invention; Fig. 2 is an enlarged plan view of the bed of the main frame, the vertically extending beams of the upright supporting frame being shown in section; Fig. 3 is a section on line 3-3 of Fig. 2; Fig. 4 is an enlarged detail vertical sectional view of the upright supporting frame; Fig. 5 is a section on line 5-5 of Fig. 4; Fig. 6 is an elevation of a modification; Fig. 7 is a vertical sectional view of the upright supporting frame of the modification; and Fig. 8 is an end view of the said upright frame.

Before proceeding with the description of the drawings I desire to call particular attention to the fact that while the invention will be hereinafter described as being applicable to dredges only, the same may be readily utilized or employed in connection with excavating machines, ditching machines or other machines of a like character.

Referring now to the drawings, the numeral 1 designates the main frame in its entirety, the said frame supporting the dredge and comprising a pair of longitudinally extending spaced apart beams 2, and transverse beams 3 which form the framework of the main frame bed illustrated in Fig. 2.

A plurality of vertically extending beams 4 are secured to the longitudinal beams 1,

the said beams 4 being braced through the medium of suitable brace beams 5 secured thereto, the beams 4 and 5 being secured at their upper extremity to longitudinally 5 extending truss-beams 6, all of which form the main frame 1 of the dredge. The frame bed comprises, in addition to the beams 2 and 3 above mentioned a plurality of longitudinally extending beams 7 and a plurality 10 of transverse beams 8, the said beams being arranged in spaced relation to form supports for a number of bearings for the operating mechanism to be hereinafter fully described.

15 Runners 9 and 10 are secured to the main frame 1, respectively, at the forward and rear end thereof, the forward runner 9 being disposed directly beneath the mast 11 of the dredge and directly beneath the point 20 where the booms 12 of the dredging apparatus are secured to the frame, while the rear runners 10 are disposed directly beneath the engine 13 carried by the frame and employed for the purpose of operating 25 the dredge and actuating the runners to subsequently appear.

An upright supporting frame, designated in its entirety by the numeral 14 is positioned centrally of the main frame, the 30 spaced apart vertically extending beams 15 of which are inclosed within or between the longitudinal beams 2 of the main frame. Runners 16 are pivotally connected at the lower ends of the vertical beam 15 as at 17. 35 Cross or longitudinally extending beams 18 connect the vertical beams 15 of the upright frame, the lower of the said beams 18 extending forwardly of the frame 14 and having connected at the forward end of the 40 said extended portion a hanger 19 which is adapted to carry a pulley 20 over which one of the operating chains to be hereinafter fully described is arranged.

Having described briefly the construction 45 of the two frames 1 and 14, the manner in which the main frame is adjusted vertically upon the said upright supporting frame will now be described. A shaft 21 is journaled within suitable brackets 22 carried by 50 the longitudinally extending beams 7 of the main frame bed, the said shaft having a pulley 23 loosely mounted upon one end thereof, the faces of the pulley having recesses 24 formed therein one of the said recesses adapted to receive a friction wheel 25 keyed or otherwise secured to the shaft 21 and the other recess adapted to receive a similar wheel 26 carried by a stub shaft 27 extending in axial alinement with the shaft 21 and journaled within a bracket 28 secured to one of the said beams 7. Operating levers 29 are arranged, one to engage the friction wheel 25 and the other to engage the wheel 26 for sliding the said 65 wheels, one at a time into frictional engage-

ment with either of the recesses of the pulley 23. Any suitable means such as a belt 29 may be arranged over the pulley 23 and a similar pulley 30 driven by the engine 13 for imparting motion to either of the said 70 shafts 21 or 27 as occasion demands.

A pinion 31 is mounted upon the stub shaft 27, the said pinion meshing into a gear wheel 32 mounted upon a shaft 33 extending parallel with the shaft 21 in spaced relation 75 thereto, the shaft 33 being journaled within suitable bearings 34 secured to certain of the longitudinal beams 7. A second pinion 34 is mounted upon the shaft 33 at the opposite end thereof from that of the gear wheel 32, the pinion 34 meshing into a gear wheel 35 mounted upon a drum shaft 36 journaled within bearings 37 carried by the said beam 7. A drum 38 is rotatably mounted upon the shaft 36, the said drum 85 having a chain 39 secured thereto, the chain 39 extending forwardly therefrom to a pulley 40 carried by a cross beam 41 of the frame bed. The chain 39 extends over the pulley 40 and rearwardly to a second pulley 90 42 carried by a movable pulley block 43. From the pulley 42 the chain continues again forwardly to a point 44 near the forward end of the frame where it is securely fastened as illustrated in Fig. 2 of the drawings. This arrangement of the chain 39 imparts movement to the pulley block 43 according to the rotation of the drum 38 and as the said pulley block 43 carries another pulley 45 over which the chain 46 is 100 arranged, the latter being arranged over pulleys carried by the upright frame it will be seen that the main frame is raised and lowered vertically upon the said upright frame by the movement of the pulley block 105 43 controlled by the rotation of the drum 38. Each end of the chain 46 is secured adjacent a pulley 47 mounted upon a carrier 48 movable longitudinally upon a track way 49 formed upon the under face of the longitudinal beams 2 of the main frame. From the point 50 where the chain 46 is secured adjacent the pulley 47 the said chain extends upwardly and over the pulley 20 carried by the hanger 19 of the upright frame, the chain extending over the said pulley 20 and downwardly to a pulley 47 over which it passes so as to extend upwardly and over a pulley 52 carried by one of the vertical beams 15 of the upright frame, the said pulley 52 being positioned near the upper end of the beam 15 or directly beneath the lower cross arm 18. The chain continues from the pulley 52 to a second pulley 53 mounted upon the carrier 48 and extends rearwardly 110 therefrom to a pulley 54 mounted upon a second carrier 55 secured to the other vertical beam 15 of the upright frame. The chain from the pulley 54 extends upwardly 115 and over a pulley 56 mounted upon the said 120 carrier 48. The chain 39 from the pulley 40 extends rearwardly therefrom to a pulley 54 mounted upon a second carrier 55 secured to the other vertical beam 15 of the upright frame. The chain from the pulley 54 extends upwardly 125 and over a pulley 56 mounted upon the said 130 carrier 48.

beam 15 opposite the pulley 52 above mentioned and depends downwardly therefrom and over a second pulley 57 of the carrier 55. From this pulley 55 the chain extends 5 rearwardly to a pulley 58 carried by one of the transverse beams 8 of the frame bed and thence toward the center of the frame to a pulley 59 carried by the same beam as the pulley 58. From the pulley 59 the 10 chain extends forwardly and over the pulley 45 of the block 43 from which point it extends over pulleys arranged in duplicate upon the opposite side of the machine where it is secured again as at 50 adjacent the pulley 47 of the carriage 48, the reference numerals for the various pulleys and carriages being the same upon both sides of the two frames as the construction and arrangement of the pulleys is identical.

20 The arrangement of the chain 46 over the pulleys 52 and 56 of the upright frame will cause the main frame to be raised or lowered with respect to the upright frame according to the rotation of the drum 38 controlled by the frictional engagement between the friction wheel 26 and the pulley 23. Rollers 60 are mounted upon each carriage 48 and 55, the rollers engaging the track way 49 formed upon the beam 2 and 30 as the said carriages, and the said upright frame are stationary it will be seen that the entire main frame is free to move forwardly upon the rollers 60 throughout the length of the track way 49 when the runners 9 and 35 10 of the main frame are withdrawn from engagement with the ground. As the main frame is lifted or raised upon the supporting frame 14 the said runners 9 and 10 are likewise lifted whereupon the entire dredge 40 is supported by the runners 16 of the supporting frame. The weight of the booms and the shovel or shovels carried thereby (not shown) will cause the main frame to tilt forwardly, this tilting movement allowing 45 the said frame to move forwardly over the rollers 60 until the rear runner 10 of the main frame comes into engagement with the rear end of the runners 16, or until the forward runner 9 again engages the ground 50 or surface upon which the dredge is supported.

The means employed for forwarding the upright frame independent of the main frame is controlled by the shaft 21 in the 55 following manner: The friction wheel 25 is thrown into engagement with the pulley 23 by the operation of the hand lever 29 thus imparting motion to the said shaft 21 according to the rotation of the driven pulley 60 30 of the engine. A gear or friction wheel 61 is mounted upon the opposite end of the shaft 21 from that of the friction wheel 25, the said wheel 61 meshing into or frictionally engaging a like wheel 62 mounted upon 65 a shaft 63 journaled within brackets 64 car-

ried by the longitudinal beams 7 of the frame bed. A gear wheel 65 is mounted upon the said shaft 63 which in turn meshes into another gear wheel 66 mounted upon a drum shaft 67 journaled within bearings 70 68 carried by the said beams 7, this arrangement of the gears and shafts rotating a suitable drum 69 mounted upon the said shaft 67. A chain 70 is secured to the drum 69, the chain extending forwardly thereupon 75 and over a pulley 71 arranged within a movable pulley block 72, from which point it extends rearwardly to a point 73 where it is secured to the frame. Another chain 74, the movement of which is controlled by the operation of the drum 69, is arranged over a pulley 75, carried by the movable block 72, the chain extending forwardly from the pulley 75 to a pulley 76 and thence to a pulley 77 from which point it extends rearwardly and over a roller 78 and is secured as at 79 to the runner 16 of the upright frame. This arrangement of the chain 74 is duplicated for each runner 16 thus causing the two runners to move in unison according to the rotation of the shaft 21.

After the rear runner 10 of the main frame is moved forwardly until its forward end engages the rear end of the runners 16, the friction wheel 25 of the shaft 21 is thrown in engagement with the power pulley 23, this engagement actuating the drum 69 and causing the chain 74 to pull the runners 16 forwardly until their forward ends engage the rear ends of the forward runners 9 of the main frame. This operation is repeated to forward or propel the dredging machine when desired, the forwarding of the machine being entirely controlled by the engine 13 mounted upon the frame bed of the main frame 1.

In reducing my invention to practice, the operation is as follows: When it is desired that the dredging machine be propelled forwardly, the main frame is first raised vertically upon the upright supporting frame 14 by throwing the friction wheel 26 into frictional engagement with the pulley 23, this engagement imparting motion to the stub shaft 27 which in turn imparts motion to the drum 38 through the medium of the several gears and shafts provided therefor. The rotation of the drum 38, by reason of the chain 39 actuates the pulley block 43, the forward movement of which actuates the chain 46 and elevates or raises the main frame upon the said supporting frame as the chain 46 is arranged over pulleys 52 and 56 as well as the pulleys of the carriages 48 and 55 carried by the said supporting frame. After elevating the main frame until the runners 9 and 10 are withdrawn from engagement with the ground, the weight carried at the forward end of the machine will cause the said main frame to

slide or move forwardly upon the rollers 60 of the said carriages until the rear runner 10 engages the stationary runner 16 of the supporting frame. When the main frame 5 has thus been moved forwardly upon the supporting frame the friction wheel 26 is thrown out of engagement with the pulley wheel 23 and the other friction wheel 25 thrown in by the operation of one of the 10 operating levers 29. This engagement between the friction wheel 25 and the pulley 23 will transmit motion to the drum 69 by means of the several shafts and pulleys arranged therebetween, and as the said drum 15 69 has a chain 70 secured thereto motion is imparted to the pulley block 72 over which the said chain 70 is arranged. As the pulley block 72 is moved by the rotation of the drum the chain 74 is actuated, such movement of the chain 74 dragging the runners 10 and the supporting frame carried thereby until the forward end of the said runners is again positioned directly behind the forward runners 9 of the main frame. 20

25 Referring now to the modification shown in Figs. 6 to 8 inclusive, the two carriages 48 and 55 have been dispensed with and one carriage 80 is provided. A chain 81 corresponding to the chain 46 of the preferred 30 form is arranged over a pulley 82 carried by the carriage 80 from which point it extends upwardly and over a large pulley 83 mounted upon one of the vertical beams 84 of the upright frame, the said beam being 35 supported by a runner 85 corresponding to the runner 16 of the preferred form. From the pulley 83 the chain depends to a pulley 86 mounted upon the carriage 80 and thence upwardly to a pulley 87 pivotally connected 40 as at 89 between curved metallic plates 90 employed for the purpose of connecting the other vertically extending beam 91 of the upright frame to the first mentioned beam 84 thereof, the said beam 91 terminating 45 before it reaches the hanger 88 so as to space the said plates 90 sufficiently apart to allow the hanger 88 to depend therebetween. From the pulley 87 the chain 81 continues 50 downwardly and is secured at any convenient point adjacent the pulley 86, this arrangement of the chain over the modified form of upright frame allowing the main frame to rise vertically with respect thereto according to the rotation of the drum 55 provided therefor.

The means employed for dragging or forwarding the said supporting frame of the modification being substantially the same as that of the preferred form a detail 60 description thereof will not be given.

It will be seen from the above, taken in connection with the accompanying drawings that the entire main frame is moved forwardly independent of the supporting 65 frame 14; that the vertical movement of the

main frame and the forward movement of the supporting frame is controlled by the driven pulley 23 into which the friction wheels 25 and 26 are adapted to be moved for frictional engagement; and that the 70 weight carried by the forward end of the main frame is sufficient to tilt the entire frame and cause the same to move forwardly upon the rollers 60 mounted upon the carriages 48 and 55 which are stationary with 75 the supporting frame 14.

In reduction to practice, I have found that the form of my invention, illustrated in the drawings and referred to in the above description, as the preferred embodiment is 80 the most efficient and practical; yet realizing that the conditions concurrent with the adoption of my device will necessarily vary, I desire to emphasize the fact that various minor changes in details of construction, 85 proportion and arrangement of parts may be resorted to, when required, without sacrificing any of the advantages of my invention, as defined in the appended claims.

Having thus fully described my invention, what I claim as new and desire to secure by Letters Patent, is:—

1. In propelling mechanism for dredges, the combination of a main frame comprising a plurality of longitudinal brace beams, 95 transverse beams arranged, one adjacent each end of said frame, a pair of drums mounted for rotation between certain of said longitudinal beams, means upon said frame for alternately rotating said drums, an upright frame extending through said main frame, a plurality of pulleys mounted upon each of said transverse beams, means connecting one of said drums and said upright frame, said means being arranged over certain of said pulleys for raising and lowering said main frame relative to said upright frame, and means connected to the other of said drums and arranged over the pulleys upon the other of the said transverse 100 means to advance said upright frame relative to said main frame, as and for the purpose set forth.

2. In propelling mechanism for dredges, the combination with a main frame, a pair 115 of drums mounted for rotation upon said frame, a first shaft, a second shaft, means driving said second shaft, means upon said second shaft movable into and out of engagement with means upon said first shaft for controlling rotation thereof, a third shaft, 120 means connecting said second shaft with said third shaft, means connecting said third shaft with one of said drums for imparting motion thereto, a fourth shaft, means connecting said first shaft with said fourth shaft for imparting motion thereto, means connecting said fourth shaft with the other of the said drums for imparting motion thereto, an upright frame extending 125

through said main frame, means connecting one of said drums to said upright frame for raising and lowering said main frame relative thereto, and means connecting the other of the said drums to the said upright frame for advancing the latter relative to said main frame, as and for the purpose set forth.

In testimony whereof I affix my signature in presence of two witnesses.

LESTER E. GESELL.
